UNITED STATES PATENT OFFICE.

HERBERT H. SCHNUPP, OF JEANETTE, PENNSYLVANIA.

LAMP-SHADE.

1,274,790.

Specification of Letters Patent. Patented Aug. 6, 1918.

Application filed February 21, 1918. Serial No. 218,512.

To all whom it may concern:

Be it known that I, HERBERT H. SCHNUPP, a citizen of the United States, residing at Jeanette, in the county of Westmoreland and

5 State of Pennsylvania, have invented certain new and useful Improvements in Lamp-Shades, of which the following is a specification, reference being had to the accompanying drawings.

10 This invention relates to certain improvements in lamp shades and has relation more particularly to a device of this general character of an inverted type and it is an object of the invention to provide a lamp shade preferably formed of glass and which is provided with novel and improved means for protecting the shade proper against injury incident to the heat radiating from the lamp with which the shade is employed, 15 and especially as resulting from the initial ignition of the lamp.

15 The invention consists in the details of construction and in the combination and arrangement of the several parts of my improved lamp shade whereby certain important advantages are attained and the device rendered simpler, less expensive and otherwise more convenient and advantageous for use, as will be hereinafter more fully 20 set forth.

The novel features of my invention will hereinafter be definitely claimed.

In order that my invention may be the better understood, I will now proceed to describe the same with reference to the accompanying drawings, wherein:

Figure 1 is a vertical sectional view taken through a lamp shade constructed in accordance with an embodiment of my invention; and

Fig. 2 is a view partly in top plan and partly in section of my improved shade as herein disclosed, the line of section being taken substantially on the line 2—2 of Fig. 1.

45 As disclosed in the accompanying drawings 1 denotes a shade formed preferably of glass and which is provided at its axial center with the opening 2. 3 denotes a metallic shield adapted to underlie the under 50 face of the shade 1 at the upper portion thereof and said shield is maintained in spaced relation relative to the shade 1 through the medium of the outstanding protuberances 4 which are preferably pressed outwardly from the shield. The protuberances 4 are arranged in circumferentially

spaced relation around the shield 3 and in staggered relation. The shield 3 is also provided at its axial center with an opening 5 defined by an upstanding marginal flange 6 insertible through the opening 2 of the shade 1. As herein disclosed the flange 6 is substantially semi-circular in cross section so that it may be effectively engaged with the shade holder of any ordinary or preferred type. Struck from the flange 6 preferably at equidistantly spaced points are the tongues 8 which are adapted to be bent outwardly and downwardly to overlie the upper portion of the shade 1 in order to maintain the shade 1 and the shield 3 in assembled relation. It is also desired that the opposite surfaces of the shield 3 have applied thereto the coatings 9 formed of suitable heat resisting and non-conducting material.

75 In practice it is thought to be self-evident that with the use of the shield 3 the heat radiating from a lamp with which the shade coacts and particularly when the lamp is first lighted, will not effect a sudden expansion of the shade 1 proper which would otherwise have a tendency to break the shade.

80 From the foregoing description, it is thought to be obvious that a lamp shade constructed in accordance with my invention is particularly well adapted for use by reason of the convenience and facility with which it may be assembled and operated and it will also be obvious that my invention is 85 susceptible of some change and modification without departing from the principles and spirit thereof and for this reason I do not wish to be understood as limiting myself to the precise arrangement and formation of the several parts herein shown in carrying out my invention in practice except as hereinafter claimed.

90 I claim:

95 In combination with a lamp shade having an opening at its axial center, a shield underlying the upper portion of the shade, the axial center of the shield being provided with an opening defined by an outstanding flange extending through the opening of the shade and affording a securing means, the portion of the shield underlying the shade being provided with protuberances contacting with the shade for holding said shield and shade in spaced relation, said 100 protuberances being in staggered relation, and means carried by the shield adjacent the

flange and engaging a marginal portion of the shade defining the axial opening in the shade for holding the shade and shield in assembled relation, the inner marginal portion of the shield terminating a material distance inwardly of the outer marginal portion of the shade.

In testimony whereof I hereunto affix my signature in the presence of two witnesses.

HERBERT H. SCHNUPP.

Witnesses:

RAYMOND R. SMITH,
HARRY G. TUSSEY.
